US0D1074966S

(12) **United States Design Patent** (10) **Patent No.:** **US D1,074,966 S**
(45) **Date of Patent:** **** May 13, 2025**

(54) **AIR PURIFIER**

- (71) Applicant: **Samsung Electronics Co., Ltd.**, Suwon-si (KR)
- (72) Inventors: **Cheolyeon Jo**, Suwon-si (KR); **Tachan Kim**, Suwon-si (KR); **Seungmok Lee**, Suwon-si (KR); **Minkyung Choi**, Suwon-si (KR); **Sodam Park**, Suwon-si (KR); **Yuna Park**, Suwon-si (KR); **Yeaseul You**, Suwon-si (KR)
- (73) Assignee: **Samsung Electronics Co., Ltd.**, Suwon-si (KR)

(**) Term: **15 Years**

(21) Appl. No.: **29/770,076**

(22) Filed: **Feb. 9, 2021**

(30) **Foreign Application Priority Data**

(57) **CLAIM**

The ornamental design for an air purifier, as shown and described.

DESCRIPTION

FIG. 1 is a front perspective view of an air purifier showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion 9 in FIG. 1;

FIG. 10 is an enlarged view of the encircled portion 10 in FIG. 1;

FIG. 11 is an enlarged view of the encircled portion 11 in FIG. 1;

FIG. 12 is an enlarged view of the encircled portion 12 in FIG. 2; and,

FIG. 13 is an enlarged view of the encircled portion 13 in FIG. 4.

The evenly-dashed broken lines in the figures depict portions of the air purifier which form no part of the claimed design.

The dot-dot-dash broken lines encircling portions of the claimed design that are illustrated in enlargements form no part of the claimed design.

1 Claim, 13 Drawing Sheets
